UNITED STATES PATENT OFFICE.

ROY H. SMITH, OF CLEVELAND, OHIO.

METAL-WORKING MACHINE.

1,239,052.

Specification of Letters Patent. Patented Sept. 4, 1917.

Application filed September 13, 1911. Serial No. 649,157.

To all whom it may concern:

Be it known that I, Roy H. SMITH, a citizen of the United States, residing at Cleveland, in the county of Cuyahoga and State 5 of Ohio, have invented a certain new and useful Improvement in Metal-Working Machines, of which the following is a full, clear, and exact description.

This invention relates to metal working 10 machines of the type wherein stock fed into the machine is cut into suitable lengths and headed, trimmed or otherwise acted upon by tools.

In various kinds of metal working machines, of this general type, the stock is cut 15 into lengths by means of a blade or shear plate carried by a reciprocating holder which is moved back and forth at right angles to the direction of feed of the stock by 20 means of a cam, the latter being usually carried by a reciprocating slide and engaging a roller mounted on the holder for the cutter proper. This roller is arranged on one 25 side of the holder, and to provide adjustment for wear of the cutter, said roller is carried by a block which is arranged in a slot of the holder and is normally held in position in the slot and is adapted for adjustment lengthwise thereof by means of an 30 adjustable screw.

This construction for cutting the stock is very satisfactory as long as the machine is operating on small stock, say $\frac{1}{4}$ or $\frac{1}{2}$ inch in diameter, but is unsuitable and defective 35 when the stock is comparatively large, say $\frac{5}{8}$ or 1 inch in diameter or thickness. As the size of the stock is increased, the pressure transmitted between the cam and roller must of course be increased, and as it is transmitted not in line with the axis of the holder or cutter, it has a certain leverage dependent substantially upon the distance of the center of the roller from the center of the 40 holder, and as a result, the cam tends to turn or rock the holder in its support or guideway. When thick stock is being cut, the holder is rocked to an extent such that a part of the cutter is swung away from the die block, so that clean shearing of the stock 45 is impossible.

A further objectionable feature of this common form of cutting mechanism wherein the roller is supported from an adjustable part mounted in a slot of the holder, lies in 50 the fact that it is not sufficiently strong and rigid to transmit the enormous pressure re-

quired to cut stock of the larger thicknesses above stated.

The object of the present invention is to provide a stock cutting mechanism for metal 60 working machines which is designed especially for cutting stock of the larger sizes without any liability of imparting a rocking movement to the holder or of bending or buckling the latter. Further, the invention 65 aims to provide such a relative arrangement and construction of the parts including the cam, roller, and cutter holder, that, not only are the above advantages attained, but the roller is amply supported and held firmly 70 without danger of breakage or displacement, while at the same time, the adjustments to provide for wear may be had.

The above and other objects are accomplished by my invention which may be 75 briefly summarized as consisting in certain novel details of construction and combinations and arrangements of parts which will be described in the specification and set forth in the appended claims.

In the drawings, Figure 1 is a plan view 80 of a metal working machine equipped with my improved stock cutting mechanism; Fig. 2 is a side view of the same with portions broken away and other parts removed; Fig. 85 3 is an enlarged horizontal sectional view showing particularly the stock cutting mechanism; Fig. 4 is a transverse sectional view of the same along the line 4-4 of Fig. 3, looking in the direction indicated by the arrows; and Fig. 5 is a sectional view of a portion of the holder showing the support for 90 two rollers which are engaged by cams to shift the holder.

Referring now to the figures of the drawing, 10 represents the horizontal bed or frame of the machine, which may be used for a variety of purposes, such as for forming bolt or rivet blanks and the like, the only essential part of the machine being the stock cutting mechanism for cutting the stock 100 which is fed into the machine, into suitable lengths, which may then be operated on by tools of any desired form.

At the forward part of the machine is a 105 crank shaft 11 which is connected by means of a connecting rod 12 to a horizontally moving slide or plunger 13, suitably guided in the frame and provided at its forward end with a tool 14 adapted to operate on the 110 stock after the latter has been cut into the required lengths by the stock cutting mech-

anism to be referred to presently. Just forward of the tool 14 is a die block 15, which may be provided with a suitable die, the particular shape or purpose of which is immaterial. The stock is adapted to be fed through an opening 16 extending through the end of the machine and through the die block, and is adapted to be cut when projected beyond the face of the die block.

At one side of the frame 10 is a frame extension 17 in which is slidably mounted for reciprocating movement in a direction parallel to the movement of the slide 13, a cutter actuating cam member or slide 18 which is reciprocated from the main shaft 11 by means of a crank disk 19 carried by the latter and a connecting rod 20 connected to the crank disk 19 and to the slide 18. By referring particularly to Fig. 4, it will be seen that the slide 18 has two cams designated 21 and 22, the former having a cam face which is considerably wider than the latter, and being arranged above the cam 22. The cutting of the stock is accomplished by means of a cutter or cutting blade 23 secured to a holder 24, which is designed to be shifted back and forth at right angles to the stock and to the direction of movement of the slide or plunger 13 and of the cam member 18. This holder 24 extends through a suitable guide opening in the side of the frame 10 and into the frame extension 17, and has a close working fit in the main frame, being engaged on one side by a gib 25, which may be adjusted to take up any wear. The holder is arranged so that the cutter 23 slides over the face of the die block 15, through which the stock is projected to be cut or sheared, as before stated.

The outer end of the holder is forked or bifurcated, as shown most clearly in Figs. 4 and 5, and in the bifurcated end is fixed a rather heavy pin or stud 26, which may be secured by means of a key 26^a in suitably provided openings in the ends of the forked portion, and in caps 26^b secured thereto. On an enlarged portion of the pin between the arms of the fork is journaled a roller 27 which is located directly in line with the axis of the holder 24, and is directly opposite to and in position to be engaged by the larger cam 21, which on being reciprocated, moves the holder and cutter inwardly to shear the stock, the pressure of the cam being transmitted to the holder directly in line with the axis of the latter. The lower end of the pin 26 is somewhat decreased in size and projects below the lower bifurcation of the holder, and journaled on the lower end of the pin is a second and smaller roller 28 which is designed to retract or positively move outward the holder and the cutter.

It will be noted that the roller supporting pin 26 is fixed in the holder and is not intended to be adjusted relative to the holder,

as in the prior constructions. To permit adjustment of the holder and cutter so as to take up any wear at the cutting edge of the cutter, I provide for an adjustment of the slide 18. This is accomplished by means of two adjustable gibs 29 and 30, against which the cam member or slide 18 bears in its reciprocating movement, the gib 29 being wider than the gib 30 and being located above the latter directly opposite or in line with the cam 21 and roller 26, and the lower and smaller gib 30 being opposite the cam 22 and roller 28.

When a length of the stock is cut off, it is held between the cutter 23 and a finger 31 supported by a pair of arms 32 and 33, the latter being connected to the holder so as to reciprocate therewith, and the former being connected to the inner free end of the arm 33 in the manner shown in Fig. 4. This mechanism, however, forms no part of the present invention, and further illustration of the same is believed to be unnecessary. The short piece of stock after it has been cut off is carried inwardly by the cutter and finger 31 until it is in line with a second opening 34, and with the tools which are to operate on the stock. It will be understood that any suitably shaped die may be carried by the die block so as to coöperate with the tool or punch 14 to produce the desired results.

With this construction wherein the roller is in line with the axis of the holder 24, it is impossible by the transmission of pressure between the cam and roller to turn or rock the holder so as to affect the action of the cutter 23, and there is no danger of the holder being bent or of buckling, providing it is suitably proportioned. Furthermore, by reason of the particular roller support and because of the fact that adjustment of the cutter is accomplished by an adjustment of the cutter actuating slide, instead of the roller, a large and well constructed bearing may be had, which can not be sheared or bent. By this mechanism, stock of any size within reasonable limits can be cut very effectively and cleanly.

Having thus described my invention, what I claim is:

1. In a metal working machine of the type wherein stock is fed into the machine and cut into sections, a frame, a stock cutting mechanism comprising a reciprocating cutter, a sliding holder carrying the cutter and arranged for movement transversely of the frame, said holder having at its outer end two rollers, one located centrally or in line with the axis of the holder, and the other at the side of the holder, and a slide provided with two cams, one adapted to engage the central roller so as to move the holder inwardly, and the other to engage the second roller to retract the holder.

2. In a metal working machine of a type wherein stock is fed into the machine and cut into sections, a frame, a stock cutting mechanism comprising a reciprocating cutter, a sliding holder carrying the cutter, said holder having at its outer end two rollers, one located centrally or in alinement with the axis of the holder, and the other at the side of the holder, a slide provided with two cams, one of which is above the other and is adapted to engage the central roller so as to move the cutter and holder inwardly, and the other adapted to engage

the second roller to cause the cutter and holder to be retracted, a guideway for the slide, including two adjustable gibs on opposite sides of the slide, one opposite the upper central roller, and the other opposite the lower roller.

In testimony whereof, I hereunto affix my signature in the presence of two witnesses.

ROY H. SMITH.
